UNITED STATES PATENT OFFICE.

GEORGES EDMOND DARIER, OF GENEVA, SWITZERLAND.

PROCESS FOR THE RECOVERY OF BENZENE HYDROCARBONS FROM COAL-GAS.

1,336,893.

Specification of Letters Patent. Patented Apr. 13, 1920.

No Drawing.

Application filed July 10, 1916. Serial No. 108,414.

To all whom it may concern:

Be it known that I, GEORGES EDMOND DARIER, a citizen of the Swiss Republic, residing in Geneva, Switzerland, have invented a certain new and useful Process for the Recovery of Benzene Hydrocarbons from Coal-Gas, of which the following is a specification.

The invention consists in a process for the recovery of benzene hydrocarbons from coal gas and is based on the fact that benzene hydrocarbons contained in coal gas are easily retained in solution in petroleum oil or in one of its refined products, when the gas is subjected to a methodical washing by means of these liquids at a temperature below $+5^{\circ}$ C., or, which is preferable, below 0° C., while at higher temperatures the portion retained is practically negligible or *nihil*.

The invention is carried out by means of any apparatus suitable for reactions between liquids and gases, but adapted, however, to maintain the temperature below $+5^{\circ}$ or better below 0° as for instance, towers, washers, absorbers, Livisey washer, atomizers and the like as now industrially employed.

Petroleum oil saturated with benzene hydrocarbons issuing from such apparatus is subsequently submitted to a partial distillation (up to about 150°) which allows the hydrocarbons to separate and possibly, for the first operation, the contained petroleum oil ethers also; the part not distilled enters again into the operation. Nevertheless, a complete distillation of the petroleum oil should be resorted to when it retains gas impurities in too large a quantity.

The cooling of the gas and petroleum oil, both of which should if possible be below 0° , can be effected either separately one after the other or both together, or only one of two may be cooled if it be sufficiently cooled for the mixture to remain below 0° , or, in every case, below $+5^{\circ}$; if the gas be separately cooled the greater part of the contained water vapor is eliminated by cooling below

0° , which dispenses with a possible desiccation by other means. 50

The cooling processes are those readily used in industry; they are based on the use of liquid gas, expansively working and other cooling machines.

It is advantageous to arrange the installations so that the cooled gas issuing from the petroleum oil absorbing apparatus serves itself to cool the entering gas; similarly for the entering and issuing liquid. In this way great economy in cooling is effected. 55 60

By way of example the following results are given.

By washing at -15° illuminating gas by means of kerosene (rectified between 200- 65 250 $^{\circ}$), this latter loads itself with benzene by hydrocarbons up to 20% of its weight and the washed gas contains in the way of substances congealable at -81° only 2 to 3% of the weight of the recovered benzene hydrocarbons. On the contrary, by washing at a temperature of $+20^{\circ}$ the weight of benzene hydrocarbons incorporated in the petroleum oil is no more than 6/100 of the quantity recovered by washing at -15° . 70 75

Having thus described the nature of my said invention and the best means I know of carrying the same into practical effect I claim:

The process of recovering benzene hydrocarbons from coal gas which consists in first washing the coal gas by petroleum oil at a temperature below plus five degrees C., then fractionally distilling from the resulting compound benzene hydrocarbon, and utilizing 80 85 the cooled and washed gas and liquid thus obtained for reducing the temperature of the entering gas and liquid.

In testimony whereof I have signed my name to this specification in the presence 90 of two subscribing witnesses.

GEORGES EDMOND DARIER.
